UNITED STATES PATENT OFFICE.

JAMES M. HARLAND, OF DAYTON, OHIO.

WRENCH.

SPECIFICATION forming part of Letters Patent No. 288,432, dated November 13, 1883.

Application filed September 4, 1883. (No model.)

To all whom it may concern:

Be it known that I, JAMES M. HARLAND, of Dayton, in the county of Montgomery and State of Ohio, have invented a new and useful Improvement in Wrenches; and I do hereby declare that the following is a full, clear, and exact description of the invention, which will enable others skilled in the art to which it appertains to make and use it, reference being had to the accompanying drawings, forming a part thereof.

My invention relates to improvements in wrenches; and it consists in the construction, combination, and arrangement of the several parts, as will be hereinafter more fully described, and specifically pointed out in the claims.

In the drawings, Figures 1 and 2 are side views, and Fig. 3 is a part side and part sectional view, of my wrench.

The wrench shown in Fig. 3 differs slightly in specific construction from that shown in the other figures, but is in principle the same, as will be described.

25 The wrench-bar A is provided at one end with the handle A', and at the other end with the jaw A², extended at right angles from what I call, for convenience of reference, the upper edge of the bar. On this upper edge, extending from the handle A' almost to the jaw A², I form a series of notches, a.

35 The movable jaw B is provided with an opening fitted to the bar A, on which it is placed and slides in the operation of the device. From the rear side of this jaw I project the flat bar b, which extends along close to the bar A, and is beveled from its upper side at its rear end, as clearly shown.

40 The slide or carriage C is placed on the bar A, and slides over the same and the bar b, as shown. It is provided in its rear portion with a mortise, c, opening onto the notched or upper edge of the bar A, and within which is placed the pawl or dog D, which is beveled on its forward edge, and is forced into engagement with the notches a by the spring d, as shown. Slots d' are cut through the walls of the carriage into the mortise c, through which are passed the screws or studs d'', by which the 45 pawl may be disengaged by hand from the notched or rack bar. In the forward portion of the carriage, in advance of the mortise c, I

form the recess c², cut down from the upper edge of the carriage, leaving the front plate or wall, c³.

55 The screw E is secured at its forward end to the jaw B, and extends back through wall or plate c³ into the recess c². The thumb-nut E', having milled edges, is turned on the rear end of the screw in the recess c², and this nut is 60 made sufficiently long on its axial line to fill the recess c² and permit the adjustment of the carriage and jaw B toward and away from each other.

65 In operation, suppose the parts in position shown in Figs. 1 and 2, and it is desired to change the size of the wrench. The nut E' may be turned from left to right. This will draw the jaw B back slightly, and the beveled end of the bar b, bearing against beveled edge 70 of pawl D, will disengage same from notches a, and the carriage may be moved to any desired point, when by turning the nut slightly in an opposite direction the dog or pawl again engages the notches, and by a further turning of 75 the screw a more delicate adjustment of the wrench is accomplished.

A slightly different arrangement is shown in Fig. 3, in which the adjusting connecting-screw is swiveled to the jaw and provided with 80 a burr, x, by which it may be revolved, and it is turned into a threaded socket in the carriage. The pawl also is held by a flat instead of a coil spring; but it will be seen that the modifications are of form only, and do not 85 vary the principle of a rack wrench-bar, a fixed jaw, a carriage having a dog engaging said rack, a movable wrench-jaw, and an adjusting-screw connecting the movable jaw and carriage.

90 It is obvious that the dog might be disengaged by hand, and that the carriage might be secured to the movable jaw by a more adjustable connection; but I prefer the construction shown and described, because it is easy, certain in action, and quick, ready adjustments are thereby accomplished.

Having thus described my invention, what I claim, and desire to secure by Letters Patent, is—

1. The combination, in a wrench, of the notched bar A, having fixed jaw A², the movable jaw B, having bar b, beveled at its rear and arranged to engage the pawl D, the car-

riage C, having spring-pawl D, beveled on its forward side, and the adjusting-screw connecting the carriage and the movable jaw, substantially as specified.

5 2. The wrench, substantially as described and shown, composed of the bar provided on its upper edge with notches and at its forward end with the fixed jaw, the movable jaw having bar b, the carriage having mortise c and

recess c', the pawl D, spring d, screw E, and nut E', all arranged and operating as and for the purposes specified.

In testimony that I claim the foregoing I append my signature.

JAMES M. HARLAND.
